UNITED STATES PATENT OFFICE.

ROBERT U. WOLFE, CHESTER T. MARTIN, AND JAMES E. HANDLIN, OF LEAD, SOUTH DAKOTA; SAID HANDLIN AND MARTIN ASSIGNORS OF ONE-HALF OF THEIR RIGHT TO VICTOR T. JEPSEN, OF LEAD, SOUTH DAKOTA.

COPY-HOLDER.

SPECIFICATION forming part of Letters Patent No. 760,094, dated May 17, 1904.

Application filed January 5, 1904. Serial No. 187,827. (No model.)

To all whom it may concern:

Be it known that we, ROBERT U. WOLFE, CHESTER T. MARTIN, and JAMES E. HANDLIN, citizens of the United States, residing at Lead, in the county of Lawrence and State of South Dakota, have invented a new and useful Copy-Holder, of which the following is a specification.

This invention relates to copy-holders for compositors, linotype operators, and copyists generally.

The object of the invention is to provide in a copy-holder of the type in which the copy is wound upon a roller as it is copied improved means for securing the copy upon the roller, improved means for imparting movement to the winding-roller, and a novel form of screen adapted to serve the double purpose of indicating the line to be copied and concealing from the view of the operator all other matter not previously copied, and so relieving the eyes of the operator of any unnecessary strain.

With the objects above mentioned and others in view, which will appear as the invention is fully disclosed, the same consists in an improved form of copy-holder, as hereinafter fully described, illustrated in preferred form in the accompanying drawings, and having the novel features thereof clearly pointed out in the appended claims, it being understood that changes in the structural details may be made without departing from the spirit of the invention or sacrificing the advantages thereof.

In the drawings, Figure 1 is a perspective view of the copy-holder in use, the movement of some of the parts being indicated by dotted-line positions. Fig. 2 is a vertical section through the copy-holder about midway between the ends. Fig. 3 is an end view of the winding-roller, showing the mechanism for releasing the gripper.

Referring to the drawings, in which corresponding parts are designated by similar characters of reference in the several views, F designates the frame of the copy-holder, which comprises a member 1, formed, preferably, of

iron or steel and having the ends 2 2 bent substantially at right angles to the main portion thereof to form brackets for the winding-roller, plates 3 3, rigidly attached to the ends 2 2 of the member 1, and plates 4 4, firmly secured upon the ends of the plates 3 3. The end portions 2 2 of the member 1 are slotted, as shown at 5 5, to receive the shaft 6 of the winding-roller, which extends through openings in the plates 3 3, secured upon the ends of the member 1 by screws or other suitable fastening members, as shown. At one end 60 the shaft 6 has rigidly attached a knurled disk or hand-wheel 7 to impart rotary movement to the winding-roller R, and at the other end a ratchet-wheel 8 is rigidly attached to the shaft and is designed to serve in connection with a pawl and operating mechanism to impart movement to the roller when such a mechanism is preferred to the hand-wheel above mentioned. The mechanism employed in connection with the ratchet 8 comprises an arm 10, which is loosely journaled upon the shaft 6 adjacent to the ratchet, a pawl 11, pivotally mounted at one end of said arm and adapted to engage the ratchet-wheel, a spring 12, which exerts a downward pull upon the end of the arm carrying the pawl, a stop 13, to limit the pivotal movement of the arm upon the shaft, a pivoted member 14, arranged at the bottom of the plates 4 and constituting a key for operating the pawl-carrying arm, and a connecting-rod 15 for imparting movement from the key to the arm 10.

The gripping mechanism upon the winding-roller comprises a rod 16, extending longitudinally of the roller and disposed in a groove 17, formed in the outer surface thereof, a gripper-plate 18, rigidly attached to the rod, a spring 19, mounted upon the roller in a recess 20 and having the end thereof engaging the outer surface of the plate 18, and mechanism at one end of the roller for turning the rod 16 and forcing the plate 18 out of contact with the roller. The rod 16 is journaled in disks 21 at the ends of the winding-roller, and an arm 22 is rigidly attached to one end 95 of the rod 16 external to the adjacent plate

18. A knurled disk 23 is journaled on the shaft 6 between the arm 22 and the adjacent end of the member 1, and studs 24 and 25 are provided upon the inner face of the disk 23. The 5 stud 24 is at a suitable distance from the center of the disk to engage the arm 22 near its inner end when the disk 23 is moved in the direction indicated by the arrow in Fig. 3, and when brought into contact with the arm 10 in this manner a slight rocking movement is imparted to the rod 16, forcing the plate 18 outward against the pressure of the spring 19 to permit introduction of papers between the plate and the roller or to enable papers to be 15 removed from the roller. The stud 25 is adapted to contact with the arm 22 when the arm has been turned sufficiently to cause the plate 18 to swing outward from the roller to the required distance, and the contact of the 20 stud 25 with the arm stops the forward movement of the disk 23 and prevents the stud 24 from passing out of engagement with the arm. The movement of the disk 23 by which the stud 24 is caused to swing the arm 22 to move 25 the gripper-plate 18 out of operative position is directly opposite in direction to the movement imparted to the winding-roller in winding the copy thereon as the copying is completed. Consequently the ratchet and pawl 30 associated with the winding-roller to impart rotary movement thereto will hold the roller against movement under the influence of the disk 23, so that the sliding movement of the disk 23 will produce only the desired effect 35 upon the copy - gripping mechanism without reversing the movement of the winding-roller.
- The preferred form of line-indicator used in connection with the copy-winding mechanism above described is a thin screen 26, formed, 40 preferably, of light sheet metal and pivotally mounted upon a rod 27, extending between the plates 4, 4, as shown. The screen 26 is preferably provided at its free edge with a plurality of slots 28, approximately an inch in depth, 45 which permit the operator to see when he has approached the end of his copy, and at the middle point of the free edge a notch 29 is formed for the passage of the spring 19, which holds the gripper-plate in operative position. 50 As may be seen in Fig. 1, the edge of the screen 26 is parallel to the axis of the shaft 6, and when the copy is evenly wound upon the winding-roller the edge of the screen will be parallel to the lines of the copy. In order to 55 hold the free edge of the screen in contact with the copy, so that it may serve as an indicator of the line to be copied, a spring is provided, which consists, preferably, of a piece of spring-wire 30, the middle portion of which extends 60 across the front of the screen 26 just below the slots 28, then downward at the sides of the screen to be wound in one or more turns around the rod 27 near its ends, the ends of the wire being disposed beneath a rod disposed 65 horizontally at the back of the copy-holder.

In order to support the copy-holder in convenient position relative to the compositor's type-case or the linotype or type-writing machine by means of which the copying is to be done, a block 31 is preferably secured upon 70 the rear surface of the supporting member 1, and a clamping-bolt 32 is extended through the block for engagement with a bracket B of any preferred construction.

The use of the copy-holder above described 75 will be readily understood from the foregoing description and the drawings illustrative thereof. The copy is passed up between the free edge of the screen 26 and the winding-roller, and the upper edge of the copy is then gripped between the plate 18 and the forward edge of the groove 17. Rotary movement is then imparted to the winding-roller by means of the knurled disk 7 or the latch mechanism at the other end of the roller to wind the copy 80 upon the roller until the first line thereof appears above the free edge of the screen 26. The line thus exposed is then copied, and movement is then imparted to the roller to bring the second line into view above the edge of 85 the screen. When the lines correspond in width to one or more teeth of the wheel 8, the step-by-step movement of the roller necessary to bring successive lines into view may be most readily brought about by depressing the 90 key 14 and so operating the ratchet mechanism connected therewith. If the lines are not such as to correspond to the teeth upon the ratchet, however, the necessary movement of the winding-roller may obviously be produced by turning the disk 7 by hand. When 95 the copying is completed, the removal of the copy from the roller may be quickly accomplished by swinging the pawl 11 out of contact with the ratchet-wheel 8 and pulling upon 100 the end of the copy. The pawl being out of contact with the ratchet-wheel, there is nothing to interfere with the reverse rotation of the roller and the copy will be allowed to unwind freely until the gripping-plate 18 is uncovered, when the pawl will be swung again 105 into engagement with the ratchet-wheel, and the disk 23 will be given a slight turning movement upon the shaft 6 to effect the release of the copy from the grip of the plate 18. 110

It will be noted that the copy-gripping plate 18 extends across substantially the entire width of the copy, so obtaining a firm hold upon the copy and preventing any tendency to tear the copy, while at the same time insuring the proper position of the copy upon the winding-roller. The mechanism by which the copy is released from the winding-roller is of very simple character, may be instantly operated, and cannot become disarranged. It 120 will also be noted that the portion of the copy exposed to view at any time comprises only the line to be copied and a few lines of the matter already copied, thus reducing to a minimum the surface exposed to view, indi- 125 130

cating clearly and positively the line to be copied and lessening the strain upon the eyes of the copyist. The indicator being provided with the slots 28 at its free edge enables the operator to tell when he is approaching the end of his copy, so that the arrangement of the lines in the transcript may be determined accordingly.

The entire structure of the copy-holder is of such character that it may be used indefinitely without appreciable wear upon any part thereof and without liability to derangement of any portion of the mechanism. All parts of the copy-holder except the body of the winding-roller, which is made of wood or other light material, are formed of metal in order to obtain sufficient strength without great bulk. The device is generally attachable to a compositor's type-case, or it may, if preferred, be supported upon a bracket mounted upon a type-writer or linotype-machine. If preferred to mount the copy-holder independently of the type-case or the machine operated by the copyist, a suitable pedestal may be employed in lieu of the bracket B, and the clamping-screws will enable the holder to be secured in any desired position.

The operation of the copy-holder with an ordinary copy has been clearly explained in the foregoing pages; but the adaptation of the copy-holder to the display of short pieces of copy which could not be secured upon the winding-roller quickly enough to justify their arrangement in the ordinary manner has not been brought out. The spring 30, which holds the screen 26 in contact with the winding-roller, forms means for effectively supporting short pieces of copy, as the spring can be instantly drawn forward from the screen 26 and the copy gripped by the spring when the copy is introduced between the spring and the screen and the spring is released. The use of the copy-holder in this manner will result in a very material saving in time when an operator has to "set up" a number of short pieces of copy, as the time necessary to secure the several pieces under the clamping-plate 18 and then bring each piece of copy into position to expose the first line thereof above the screen is saved.

Having thus described the construction and use of our invention, what we claim as new, and desire to secure by Letters Patent, is—

1. In a copy-holder, a winding-roller having a gripper member mounted on the roller, means carried by the roller for forcing said gripper member into engagement with the copy, and means also carried by the roller for throwing said gripper member into inoperative position.

2. In a copy-holder, a winding-roller having a groove extending longitudinally thereof, a gripper member pivoted in said groove, means on the roller for pressing said gripper mem-

ber against the surface of the roller, and means also carried by the roller for forcing said gripper member out of contact with the surface of the roller.

3. In a copy-holder, a winding-roller having a groove extending longitudinally thereof, a gripper member pivoted in said groove, a spring mounted on said roller to press said gripper member against the copy, said spring being disposed circumferentially of the roller, and means carried by the roller for throwing said gripper member into inoperative position.

4. In a copy-holder, a winding-roller having a groove extending longitudinally thereof, a gripper-plate extending longitudinally of the roller and pivotally mounted in said groove, a spring disposed circumferentially of the roller and let into the surface thereof, said spring being fixed at one end and having the other end arranged to press upon the outer surface of said gripper-plate, and means carried by the roller for forcing said gripper-plate outward from the roller against the action of said spring.

5. In a copy-holder, a winding-roller, a gripper member carried by the roller and normally held in operative position, and mechanism including a hand-wheel and an arm operated thereby for throwing said gripper member into inoperative position.

6. In a copy-holder, a winding-roller having a groove disposed longitudinally thereof, a rod having a gripper-plate rigidly attached thereto disposed in said groove and arranged for rocking movement, means for holding the gripper-plate normally in operative position, an arm fixed upon said rod, and mechanism carried by said roller and arranged for limited rocking movement relative thereto to engage said arm and throw said gripper-plate into inoperative position.

7. In a copy-holder, a winding-roller including a shaft and having a longitudinally-disposed groove on the surface thereof, a rod disposed longitudinally in said groove and arranged for limited rocking movement, a gripper-plate rigidly attached at one side to said rod, means upon the roller for holding said gripper-plate normally in operative position, an arm fixed upon said rod, a disk journaled upon the shaft of the winding-roller and adjacent to said arm, said disk having projections on the surface thereof for engagement with said arm to impart movement thereto when the disk is given a slight turning movement upon the shaft and to limit the extent of such turning movement.

8. In a copy-holder, a winding-roller, a combined copy-screen and line-guide pivotally mounted adjacent to said roller and having one edge in contact with said roller, and a spring extending longitudinally of said screen and line-guide near the free margin thereof, said

spring engaging the front surface of said screen and line-guide to hold it in contact with said roller.

9. In a copy-holder, a winding-roller, means for imparting movement to said roller, and a copy-screen having one edge parallel to the axis of said roller and held normally in contact with the roller, said screen being provided at the edge in contact with the roller with a plurality of slots.

In testimony that we claim the foregoing as our own we have hereto affixed our signatures in the presence of two witnesses.
